ors to Johnson Laboratories, Inc., Chicago, Ill.,
a corporation of Illinois

Application March 14, 1938, Serial No. 195,766

6 Claims. (Cl. 171—119)

Our invention consists of a permeability tuned coupling device in which first and second inductive windings are mounted in coupled relation, each of said windings being provided with an iron core which is movable relatively to the associated winding for tuning purposes, the cores being preferably of comminuted magnetic material, combined with a suitable binder and compressed into solid condition. The windings are electrically connected with fixed condensers forming a part of the coupling device, so that the said condensers effect the greater part of the tuning of the circuits in which they are included, to a desired frequency, the adjustment of the cores being usually employed to accurately tune said circuits to resonance at the desired frequency, after the coupling device is electrically connected for use. Our coupling device is intended principally for use as the coupling means between the intermediate frequency stages of radio receivers, for example of the superheterodyne type.

In connection with coupling devices of the kind described, it is frequently desired that the tuning of the circuits of the coupling device may be effected independently of each other and from the same end of the coupling device, for example the end thereof that is remote from the mounting plate supporting the device in the radio receiver. By our invention we provide novel means for effecting independent adjustment of the cores of the coupling device, from the same end of said device, and we also provide novel means for mounting the fixed condensers of the coupling device on the supporting structure thereof.

The above and other objects of our invention will more clearly appear from the description of the drawing illustrating our invention, in which—

Fig. 1 is a central, vertical, sectional view taken longitudinally through the coupling device, this view being to an enlarged scale and taken along the line 1—1 in Fig. 2;

Fig. 2 is a vertical, sectional view of the structure illustrated in Fig. 1, taken along the line 43 2—2;

Fig. 3 is a vertical, sectional view of the structure shown in Fig. 1, taken along the line 3—3;

Fig. 4 is a vertical, sectional view of a part of the structure shown in Fig. 1, taken along the line 44—44, and

Fig. 5 shows in elevation, one of the stud screws preferably used in connecting parts of the structure shown in Figs. 1 and 2.

Similar numerals refer to similar parts throughout the several views.

As shown in Fig. 1, our coupling device consists of a supporting bar or member 10, for example, of brass or other suitable material, which is U-shaped, so that its end portions 10a and 10b extend substantially parallel with each other and across the longitudinal axis of the device, the body portion of said member being adjacent and substantially parallel with one side wall of a metallic shielding can 11 employed to enclose the coupling device. The end portions 10a and 10b of the member 10, are provided with apertures coaxial with the axis of the coupling device, to receive the end portions of a tube 12 of insulating material, on which the inductance windings 13 and 14 of the device are mounted. To hold 10 the tube 12 in place in the supporting member 10, the ends of said tube are preferably flanged outwardly against the outer surfaces of the end portions 10a and 10b of said supporting member, as shown at 12a and 12b. While the inductance 20 windings 13 and 14 may be of any desired size and proportions, we prefer to construct each of the windings in a plurality of parts, spaced from each other as indicated and connected in series with each other, all of the parts of each of said 25 windings so connected, being herein designated as one of the inductance windings of the coupling device. The windings 13 and 14 are spaced from each other on the tube 12 by an amount that will effect the desired degree of coupling between 30 said windings, and magnetic cores 15 and 16 are located in the tube 12 in inductive relation with the windings 13 and 14 respectively, said cores being preferably of comminuted magnetic material 35 combined with a suitable binder and compressed into solid condition, and of an outer diameter to move freely in the tube 12 supporting them. While the cores 15 and 16 may have any desired form, we prefer to make them tubular to facilitate their connection with adjusting 40 screws 17 and 18 by means of connecting members 19 and 20 of resilient material, for example rubber compound, which extend through the holes in the cores in compressed condition.

The end portion 10b of the supporting member 45 10, has secured to it by stud screws 21, 21, as illustrated in Fig. 2, a plate 22, for example, of metal or other suitable material which extends across the end of the tube 12 and clamps the flange 12b thereof against the end portion 10b. 50 The plate 22 is provided with a threaded aperture coaxial with the axis of the coupling device, for threaded engagement with the adjusting screw 18, so that by turning the said adjusting screw, the core 16 may be withdrawn towards 55

the plate 22, from within the winding 14, to any extent that may be desired, the core 15 being illustrated in Fig. 1, in its completely inserted position relatively to the winding 14, and therefore in its position producing a maximum inductive effect of said winding. The upper end portions of the plate 22 and of the end portion 10b of the supporting member 10, are provided with clearance apertures for an adjusting screw 23, 5 having a flange 23a frictionally held between the plate 22 and the upper end of the portion 10b. The adjusting screw 23 is disposed substantially parallel with the tube 12 and a washer 24 of resilient material, for example felt, is disposed between the flange 23a and the end portion 10b of the supporting member 10, to prevent axial play of the adjusting screw 23, when the plate 22 is tightly clamped to the supporting member by the adjacent screw 21, without interfering with 15 turning said screw 23 for adjustment purposes. The threaded portion of the adjusting screw 23 extends through and engages corresponding threads in the downwardly bent end portion of an operating bar 25, which extends longitudinally 20 of the device and through a guiding slot 10c in the end portion 10a of the supporting member 10. Outside of the end portion 10a of the supporting member, the operating bar 25 is bent as indicated at 25a, substantially parallel with the end portion 10a, and extends across the axis of the tube 12, said bent end portion 25a being provided with 25 a threaded aperture coaxial with the tube 12 for threaded engagement with the screw 17, which is held in any desired adjustment relatively to the operating bar by a clamping nut 26. As a result of this construction, turning the adjusting screw 23, moves the operating bar 25 longitudinally of the device and imparts corresponding axial movement to the core 15 for tuning purposes. The adjusting screws 18 and 23 extend 30 through clearance apertures therefor in the can 11, so that said adjusting screws may be operated after the can is in place, and from the end of the coupling device remote from the plate on which the coupling device is mounted.

The shielding can 11 is held on the studs 21 by suitable nuts as indicated for one of said studs at 27 in Fig. 1, and the supporting member 10 is further held in place in said can by a 35 screw 28 extending through said can into said supporting member. The can having the coupling device mounted therein as described, is conveniently supported on any desired mounting plate 29 by means of threaded lugs 30 extending 40 from the end of said can and engaging nuts 31 to hold the can in place.

As shown in Fig. 2, the plate 22 has extending therefrom a tongue 22a engaging the mid-portion of a spring 32, the end portions of which 45 spring press against the adjusting screws 18 and 23 and tend to hold said screws in any ad-justed positions.

The member 10 has secured thereto fixed condensers 33 and 34, by metal staples 35 and 36 50 extending around said condensers and through apertures in said supporting member so that the end portions of the staples are between the supporting member and the adjacent side wall of the shielding can 11. The condenser 33 is 55 connected with the terminals of the winding 13 by wires 37, 37 and the condenser 34 is connected with the terminals of the winding 14 by wires 38, 38.

As shown for the condenser 33 in Fig. 4, the 60 outer insulating material of the condensers is

provided with recesses 33a, 33a engaged by corresponding projections 10d formed on the upper surface of the supporting member 10 to prevent lateral displacement of the condensers on the supporting member. As a result, the staples 35 5 and 36, by holding the recesses and projections securely in engagement with each other, prevent displacement of the condensers in any direction relatively to the supporting member.

The adjusting screws 17 is employed to secure 10 proper position of the core 15 relative to the winding 13, when the adjusting screw 23 is in either of its positions of extreme adjustment, after which the nut 26 is tightened and the screw 17 is not further used in tuning the coupling 15 device, all adjustments to compensate for the capacity of connecting wiring being effected by the adjusting screws 18 and 23 for the circuits including the windings 14 and 13 respectively, so that each of said circuits may be accurately 20 brought to a resonant condition at the frequency for which the coupling device is designed, after the coupling device is electrically connected with the apparatus with which it is to be used.

In making use of the expression permeability 25 tuning in connection with the inductance windings, we refer to effecting inductance changes in said windings, by changing the permeability of the magnetic paths of said windings by the movement of magnetic cores relatively to said 30 windings.

While we have shown our invention in the particular embodiment above described, it is understood that we do not limit ourselves to the particular constructions illustrated in carrying out our invention, as we may employ equivalents thereof without departing from the scope of the appended claims.

Having thus described our invention, what we claim is:

1. In a permeability tuned intermediate frequency coupling device, the combination of a tube of insulating material, two inductance windings mounted on said tube and spaced for desired coupling between them, a core of compressed comminuted magnetic material in said tube for each of said windings, first and second adjusting screws connected respectively with said cores and extending from the ends of said tube to move the cores axially in said tube, a U-shaped bar having its ends engaging and supporting said tube, said bar ends being extended substantially beyond said tube, a plate secured to one end of said bar and extending across the adjacent end of said tube, said plate having a threaded aperture engaging the threads of said first adjusting screw, a third adjusting screw extending through said one end of said bar and through said plate and substantially parallel with said first screw, said third screw having a flange between said bar and said plate restraining said third screw from axial movement, and an operating bar having bent ends in threaded engagement respectively with said second and said third screws, whereby rotation of said third screw moves said operating bar longitudinally and thereby moves said second screw and the core connected therewith axially in said tube.

2. In a permeability tuned intermediate frequency coupling device, the combination of a tube of insulating material, two inductance windings mounted on said tube and spaced for desired coupling between them, a core of compressed comminuted magnetic material in said tube for each of said windings, first and second

- adjusting screws connected respectively with said cores and extending from the ends of said tube to move the cores axially in said tube, a U-shaped bar having its ends engaging and supporting said tube, said bar ends being extended substantially beyond said tube, a plate secured to one end of said bar and extending across the adjacent end of said tube, said plate having a threaded aperture engaging the threads 0 of said first adjusting screw, a third adjusting screw extending through said one end of said bar and through said plate and substantially parallel with said first screw, said third screw having a flange between said bar and said plate 5 restraining said third screw from axial movement, an operating bar having bent ends in threaded engagement respectively with said second and said third screws, whereby rotation of said third screw moves said operating bar longitudinally and thereby moves said second screw and the core connected therewith axially in said tube, and a washer of resilient material engaging the flange of said third screw and tending to hold the latter in adjusted position.
5. In a permeability tuned intermediate frequency coupling device, the combination of a tube of insulating material, two inductance windings mounted on said tube and spaced for desired coupling between them, a core of compressed comminuted magnetic material in said tube for each of said windings, first and second adjusting rods connected respectively with said cores and extending from the ends of said tube to move the cores axially in said tube, a U-shaped member having its ends engaging and supporting said tube, said member ends being extended substantially beyond said tube, a plate secured to one end of said member and extending across the adjacent end of said tube, said plate having a threaded aperture engaging the threads 0 of said first adjusting screw, a third adjusting screw extending through said one end of said member and through said plate and substantially parallel with said first screw, said third screw having a flange between said member and said plate restraining said third screw from axial movement, and an operating bar having bent ends in threaded engagement respectively with said second and said third screws, whereby rotation of said third screw moves said operating bar longitudinally and thereby moves said second screw and the core connected therewith axially in said tube, said operating bar having sliding engagement with said supporting member restraining said operating bar from lateral movement.
5. In a permeability tuned intermediate frequency coupling device, the combination of a tube of insulating material, two inductance windings mounted on said tube and spaced for desired coupling between them, a core of compressed comminuted magnetic material in said tube for each of said windings, first and second adjusting screws connected respectively with said cores and extending from the ends of said tube to move the cores axially in said tube, a U-shaped member having its ends engaging and supporting said tube, said member ends being extended substantially beyond said tube, a plate secured to one end of said member and through said plate and substantially parallel with said first screw, said third screw having a flange between said member and said plate restraining said third screw from axial movement, an operating bar having bent ends in threaded engagement respectively with said second and said third screws, whereby rotation of said third screw moves said operating bar longitudinally and thereby moves said second screw and the core connected therewith axially in said tube, and a washer of resilient material engaging the flange of said third screw and tending to hold the latter in adjusted position.
5. In a permeability tuned intermediate frequency coupling device, the combination of a tube of insulating material, two inductance windings mounted on said tube and spaced for desired coupling between them, a core of compressed comminuted magnetic material in said tube for each of said windings, first and second adjusting rods connected respectively with said cores and extending from the ends of said tube to move the cores axially in said tube, a member adjacent one end of and supporting said tube, a plate secured to said member and extending across the end of said tube, said plate having an aperture receiving one of said first and second rods with threaded engagement, an adjusting screw having a fixed support spaced laterally from said tube, and an operating bar having bent ends respectively in engagement with the other of said first and second rods and with said screw, said screw having means restraining it from axial movement relatively to its said support.
6. In a permeability tuned intermediate frequency coupling device, the combination of a tube of insulating material, two inductance windings mounted on said tube and spaced for desired coupling between them, a core of compressed comminuted magnetic material in said tube for each of said windings, first and second adjusting rods connected respectively with said cores and extending from the ends of said tube to move the cores axially in said tube, a member adjacent one end of and supporting said tube, a plate secured to said member and extending across the end of said tube, said plate having an aperture receiving one of said first and second rods with threaded engagement, an adjusting screw having a fixed support spaced laterally from said tube, and an operating bar having bent ends respectively in engagement with the other of said first and second rods and with said screw, said screw having means restraining it from axial movement relatively to its said support.
6. In a permeability tuned intermediate frequency coupling device, the combination of a tube of insulating material, two inductance windings mounted on said tube and spaced for desired coupling between them, a core of compressed comminuted magnetic material in said tube for each of said windings, first and second adjusting rods connected respectively with said cores and extending from the ends of said tube to move the cores axially in said tube, a member adjacent one end of and supporting said tube, a plate secured to said member and extending across the end of said tube, said plate having an aperture receiving one of said first and second rods with threaded engagement, an adjusting screw having a fixed support spaced laterally from said tube, and an operating bar having bent ends respectively in engagement with the other of said first and second rods and with said screw, said screw having means restraining it from axial movement relatively to its said support, said fixed support including said member and said plate, and said restraining means comprising a flange on said screw between said member and said plate.
